UNITED STATES PATENT OFFICE

HERMAN H. KISTNER, OF BALTIMORE, MARYLAND

CLOSURE FASTENING AND LOCKING MEANS

Application filed March 17, 1932. Serial No. 599,547.

This invention relates to window sash locks and similar devices and aims generally to provide improved locking means comprising means for bolting members such as window sashes against relative opening movement together with means for drawing such members toward each other in a direction transverse to the direction of relative opening movement thereof to prevent rattling of the same or 10 close the space between such members or achieve both these results, among others appearing hereinafter.

Subsidiary to this general object, my invention further aims to provide improved bolting means, certain features of which may be employed in other relations than those herein particularly described. In addition my invention aims, severally and interdependently, to improve the details of construction of such 20 subsidiary bolting means, to provide improved operating means therefor, to provide a novel locking means and appurtenances thereto, and to provide a novel association with suitable member drawing means of 25 such subsidiary bolting means and appurtenances.

Other objects and particular advantages of various features and combinations of my invention will be made clearly apparent to 30 those skilled in the art by the following detailed description of preferred embodiments of my invention shown in the accompanying drawings, in which

Fig. 1 is a transverse section through the 35 meeting rails of a pair of window sashes secured by a device illustrating my invention, parts of which are shown in section;

Figs. 2 and 3 are sectional views taken upon planes at right angles to the section of 40 Fig. 1, respectively at the lines 2-2 and 3-3 of Fig. 1, looking in the directions indicated by the arrows thereon;

Fig. 4 is a view similar to Fig. 1 but illustrating the cooperation of a key with the 45 structure of Fig. 1;

Fig. 5 is a phantom perspective view of the installation of Figs. 1-4;

Fig. 6 is a disassembly view of the subsidiary bolting means and operating means therefor which are incorporated in the device 50 of Figs. 1-5; while

Fig. 7 is a view similar to Fig. 3 showing a simplified form of subsidiary bolting means; and

Fig. 8 is a disassembly view of the barrel 55 and bolt elements of such simplified form of subsidiary bolting means.

The embodiment of my invention, an illustrative form of which is shown in Figs. 1 through 6 of the drawings herewith, comprises a rotary bolt similar to any such bolt commonly used with catch-means for engagement thereby to secure the meeting rails of closures of any ordinary type, such as sliding sash windows, casement windows or the like, and the form shown to illustrate such device and the association thereof with a conventional closure, comprises a rotary cam bolt 10 provided with a base or attaching plate 11 mounted upon the meeting rail 12 of a sliding sash window and a hook-catch 13 mounted upon the meeting rail 14 of the companion sash of the window.

This much of my device may be of any desired or conventional form, as my invention resides in other devices of the embodiment shown, the association of such other devices with the rotary bolt means, and such particulars of construction as are employed to effect such association, the respective constructions and associations of which are hereinafter more fully described.

As shown in Figs. 1 through 6, these other devices comprise a projectable bolt which is adapted to be secured in one of the closure 85 members (in the form shown by being driven into a hole formed therein) in position to be projected to engage with the cooperating closure member; means to interconnect a rotary bolt and a projectable bolt to render one of 90

them capable of controlling the operation of the other; means to lock at least one of the bolts, and preferably the projectable bolt, in engaged position so that unlocking means, shown as a key (see Fig. 4), must be employed to release the bolt when provided with such locking means; means applicable when locking means is provided for the projectable bolt to prevent forcing of the same from locked position if it has exposed means normally utilized to move the same; and means such as a lost motion device to provide, when locking means is associated with a rotary-cam-bolt, for drawing movement of said cam-bolt within the locked range thereof.

The construction and operation of these several devices, which may be designed in various forms and associated in various combinations, as above indicated, may be most readily comprehended from a single description of the comprehensive device of Figs. 1 through 6, in which all of them are embodied.

In this device the projectable bolt comprises a tubular body member 15 provided with a separable sleeve portion 15^a and in which is mounted a bolt member 16, provided with engageable means, as the rack 17, exposed through an opening 18, 18^a, in the side of the tubular body 15, 15^a. In the form shown, the rack 17 extends into the opening 18, 18^a and is secured in a recess 19 in the bolt member 16 (see Figs. 3 and 6) by means of a machine screw 20 extending through the bolt member 16 and having its head countersunk therein, and the tubular body is provided with an opening 21 (Fig. 3) so that the bolt 16 may be slid into the body member and have the rack 17 thereafter attached thereto. With this simple construction the rack 17 not only provides an engageable portion for moving the bolt 16, but by cooperating with the opening 18, 18^a, provides means for limiting the throw of the bolt member 16 or preventing rotation thereof in the body 15 and may serve both these functions, as in the form shown, as well as other functions hereinafter described. The tubular body, as pointed out hereinafter, in connection with Figs. 7 and 8, need not necessarily be made in two separable parts, but this construction is embodied in the device of Figs. 1 through 6 because it is particularly advantageous in connection with the particular locking means disclosed therein and hereinafter described.

In the illustrative embodiment of my device the side wall at one side of the opening 18 is cut away as indicated at 22, so that the means for operating the bolt 16, hereinafter described, may engage with the rack 17 without its being necessary to extend the rack beyond the confines of the tubular body 15, so that the rack will not interfere with the driving of the projecting bolt into the closure member 12 in mounting it as shown. In the forms shown the other side of the opening 18

is not cut away, but is left intact to form a seat 23 against which the member for engaging the rack 17 or the like may rest, if desired, and against which premature abutment of such member will indicate failure to properly align the projectable bolt assembly in inserting the same, when the elements of the device are provided and inserted separately, as shown.

The interconnecting means of this embodiment for enabling the rotary bolt 10 and the projectable bolt 15-16 to mutually control each other's operation is best shown in Figs. 3 and 6 of the drawings and comprises means such as the axially extending shaft 25 secured at its end portion 26 to rotate with the rotary bolt member 10 in any suitable manner as by riveting it in place in a sleeve 27 secured to the rotary member 10 and rotatably attaching the same to the base or mounting plate 11, as shown in Figs. 1 through 5. In Fig. 6 I have shown the end portion 26 screw threaded, a construction which may be employed if it is desired to secure the interconnecting means to an existing peculiar rotary bolt by drilling the latter and employing a nut and lock washer to effect the connection. This screw threaded construction is also advantageous for the attachment of a simple operating handle if it is desired to use the projectable bolt and its operating means without correlating it with a rotary bolt. At its extended end, which projects beyond the attaching face of the mounting plate 11, the axial shaft 25, in the form shown, carries suitable engaging means, such as the pinion 28, to cooperate with the rack 17 or other cooperating engageable means on the bolt 16, to drive the latter as the shaft 25 is rotated. In the form shown, in which the projectable bolt assembly is separate from the rotary bolt and axial shaft assembly, the parts are assembled in proper relation by drilling accurately positioned holes in the closure member 12, as shown, and inserting the parts therein, and to prevent loosening of the shaft 25 after use, or springing of the pinion 28 out of engagement with the rack 17, a bearing sleeve 29 is loosely mounted on the shaft 25 to tightly fit and line the hole into which the shaft and sleeve are inserted. When applying the rotary bolt 10 and interconnecting means 11 as a complete assembly, as indicated in Figs. 1-5, if friction of the sleeve 29 in the hole causes it to bear against a rotary portion of the rotary bolt assembly, as the lower end of the flanged sleeve 27, and cause stiffness of operation, this may be remedied by lightly tapping with a hammer such part of the device as will apply force to the bearing sleeve 29 to drive the same slightly into the hole. In the form shown the end 26, sleeve 27 or an adjacent portion of the base 11 may be

tapped to loosen the engagement of the sleeve 29 with the lower flange of the sleeve 27. As aforementioned, the device of Figs. 1 through 5 and the subsidiary shown in Fig. 6, comprises means to lock at least one of the bolts, and preferably the projectable bolt, in engaged position so that unlocking means must be employed to effect release of the same. In the form shown, this locking means (illustrated in Figs. 1, 4 and 6) is provided by forming a transverse bore 30 in the bolt member 16 and mounting therein a detent 31 urged outwardly by means such as a coil spring 32, to engage with an inwardly opening detent socket 33 formed in the tubular body 15. In the form shown, this locking means 30-33 directly locks the projectable bolt 16 in engaged position, and indirectly, by virtue of the interconnecting means 25-29 locks the rotary bolt 10 in engaged position.

Within the broad purview of my invention, any suitable means may be provided for displacing the locking means or detent 31, but for the sake of simplicity I prefer to provide for direct operation thereof by a detent depressing member, and accordingly provide an opening for the insertion of such a member leading into the detent socket 33. In the illustrative embodiment of my invention this opening is shown as a longitudinal groove 34 (see Figs. 1, 4 and 6) formed in the tubular body 15-15^a and extending into the detent socket 33. In the construction shown, to insure a clear key channel and avoid the projection of wood fibres from the member 12 into the detent socket 33 and groove 34, the outer sides thereof are closed, the closure being effected, for simplicity of manufacture, by the separate sleeve or shell 15^a. By the use of these separate parts the socket 33 and groove 34 may be formed to extend entirely through the member 15, as best shown in Fig. 6, and in addition, the shell 15^a may be readily formed with a flanged end face 35 to lie flush with the closure member 11 and give a finished appearance to the installation as indicated in Fig. 5. This flanged face 35, as shown, may be provided with slots 36 aligned with the key channel 34 and as many cooperating guide channels 34^a as desired to cooperate with the key, and these slots will be maintained in alignment by any suitable means, which, in the form shown comprises the edges of the opening 18^a engaging with the sides of the rack-member 17.

If the projectable bolt assembly of Figs. 1 through 6 should turn about its axis during insertion thereof in the closure member 12, the grooves 34, 34^a, slots 36, 36^a, and relatively large central opening in the end face of the member 15^a enable a turning tool with lateral projections to be inserted through the face plate to engage the grooves 34-34^a to turn the member until the rack 17 or other

engageable element is properly positioned for engagement. In case such grooves are not provided (as in the simplified form of my invention shown in Figs. 7 and 8, in which the locking means is omitted and in which parts similar to those of the comprehensive embodiment of my invention are indicated by similar, but primed, reference numerals) the provision of an orifice 34^b (Fig. 8) located to be covered by the member 12 upon full insertion of the projectable bolt assembly, may be used to enable the assembly to be inserted to a considerable extent and then be aligned by the application of a turning tool to the orifice 34^b before the assembly is completely driven home. If desired the end of the slot 18^a at 34° (see Fig. 8) may be used for this purpose.

When locking means is associated with a projectable bolt having exposed means for operating the same, such as a handle or the handle of the rotary bolt 10 in the form shown, my invention contemplates the provision of means to insure against forcing of the bolt from locked position, and one or more such means may be provided, in the forms shown in Figs. 1 through 6, preferably by rendering one or more portions of the operating means for the bolt 16 less resistant to forcing than the detent 31. Such less resistance may be obtained either by providing for breakage or for slippage of a part of such operating means under the strain of a force less than that required to shear the pin 31, and in the form shown the provision of relatively weak teeth on the rack 17 and pinion 28 will provide for stripping of these teeth before shearing of the pin 31, or the provision of a frictional connection of the pinion 28 to the shaft 25 as shown, if not of excessive tightness, will enable slippage at such connection before shearing of the pin 31. My invention contemplates the use of frangible or slippable connections, or both, in this regard, and when employing both, I prefer to make the slippable connection of a character intended to yield before the frangible connection, so that the parts can be forced back to original position after an attempt to force the lock, the frangible connection being a safety assuring feature in the event of failure of the slippable connection to yield as intended.

As an additional safety feature, when the lock is applied to a closure such as a window sash I provide a socket liner 40, hardened at least at its closed end, to prevent access being obtained to the bolt member 16 by drilling through from the exterior of the member 14. This liner 40 is preferably deep enough to provide a clearance space 41 beyond the end of the bolt-member 16, when the latter is projected, at least sufficient to provide for abutment of the liner 40 against the body 15 before the liner will contact the bolt-member 130

16, so that the liner 40 cannot be driven against the bolt-member 16 to drive the latter from projected position or to shear the locking detent 31. With this construction the 5 only possible way to disengage the projectable bolt from the exterior would be to drive the entire assembly inwardly, out of engagement with the closure member 14, a procedure necessitating considerable noise. As 10 a further precaution the liner 40 may be provided with a laterally extending continuous flange or lugs indicated at 42', Fig. 7, to abut the closure member 11 and entirely prevent driving out of the assembly. 15 In the illustrative embodiment of my invention in which the locking means is associated with a rotary cam bolt used to draw the closure members into mutually engaging or non-rattling position, a lost motion device 20 or arrangement to enable drawing movement of the cam-bolt within the locked range thereof is provided, and for simplicity such device is preferably embodied by arranging for continued movement of the parts after 25 the detent 31 enters the detent socket 33. In the form shown, in which the detent is maintained in alignment with the key opening because of the guidance of the rack 17 in the opening 18, 18^a, this is very simply accomplished, merely by drilling the detent socket 33 sufficiently larger in diameter than the detent 31, as shown, to enable such additional rotation of the rotary cam-bolt as is desired. 30 As shown in the drawings my invention 35 provides a secure projectable fastener entirely invisible from the exterior of a window to which it may be applied, and the inner end face 35 of which, when exposed as shown, lies flush with the surface of the member to 40 which it is applied. In addition, my invention provides for entry of the projectable bolt-member 16 into the body proper of the cooperating closure member 14, as distinguished from entry into a member merely 45 screwed thereon, which might easily be pulled off the closure member by "jimmying" the closure. Thus my invention in the forms disclosed prevents "jimmying" of the closure or so called "slicing" thereof (i. e. disengagement 50 of the fastening by a blade slipped between the closures), and in forms such as that of Figs. 1 through 6, prevents unlocking of the closures even if a hand-hole be cut through the closure. 55 With the double-fastening device of my invention applied to cooperating closure members as shown, mere closure of the members and turning of the rotary bolt in the usual way effects the usual fastening of the 60 members and in addition effects entry of the projectable bolt into the body proper of the member with which it engages; while at the same time, in the form shown in Figs. 1 through 6, the locking means provided automatically comes into play to prevent unfas-

tening of the closures. To unlock the device of Figs. 1 through 6 it is only necessary, as indicated in Fig. 4, to insert the wedge-shaped key 45 to depress the detent and enable unfastening of the bolts by the usual manipulation of the rotary bolt while the key is in place. 70

It is of course clear that the several features and combinations of my invention may be embodied in other forms than those disclosed to illustrate the same, and that the specific embodiments particularly described herein are to be considered merely illustrative and not restrictive of my invention. 75

I claim as my invention:

1. A sash-lock comprising a tubular body having an internally open detent socket and an opening leading thereto, a bolt member and means for sliding the same in said tubular body to retracted and projected positions, a transverse bore in said bolt member, a detent pin slidable in said bore, a spring arranged to urge said pin to a position extending into said socket, said sash lock being adapted to be released by unlocking means shaped to enter said opening in said tubular body and to depress said pin to a position to disengage the same from said socket. 80

2. A sash-lock comprising a tubular body having an internally open detent socket and a longitudinal key groove extending into said socket, a bolt member and means for sliding the same in said tubular body to retracted and projected positions, a transverse bore in said bolt, a detent pin slidable in said bore, a spring arranged to urge said pin to a position extending into said socket, said sash lock being adapted to be released by unlocking means shaped to slide in said longitudinal groove in said tubular body and to depress said pin to a position to disengage the same from said socket. 95

3. A sash-lock comprising a tubular body having an internally open detent socket and an opening leading thereto, a bolt member and means for sliding the same in said tubular body to retracted and projected positions, a transverse bore in said bolt, a detent pin slidable in said bore, a spring arranged to urge said pin to a position extending into said socket, said sash lock being adapted to be released by unlocking means shaped to enter said opening in said tubular body and to depress said pin to a position to disengage the same from said socket, said bolt sliding means including a connection less resistant to forcing than said detent pin to prevent forcing of said bolt when said detent pin is engaged in said socket. 100

4. A sash-lock comprising a body member, 105 a bolting member slidable therein to retracted and projected positions, means for sliding said bolting member, means for locking said bolting member in projected position, said sash lock being adapted to be released by 110

means for unlocking said bolt locking means, said bolt sliding means including a connection less resistant to forcing than said bolt-locking means to prevent forcing of said bolt when 5 locked.

5. In combination, a rotary cam bolt of the window-fastening type and means for locking the same in engaged position, said locking means being arranged to provide lost motion 10 to enable member drawing movement of the cam bolt within the locked range thereof.

6. In combination, closure fastening means comprising a rotary-bolt of the window-fastening type and catch-means for engagement 15 thereby, a projectable-bolt adapted to be mounted in the closure member upon which said rotary-bolt is to be mounted and to be projectable to a position engaging the closure member with which said catch-means is to be 20 associated and means to connect said rotary bolt and projectable-bolt for simultaneous operation.

7. In combination, closure locking means comprising a rotary-bolt of the window-fas- 25 tening type and catch means for engagement thereby, a projectable bolt adapted to be mounted in the closure member upon which said rotary-bolt is to be mounted and to be projectable to a position engaging the closure 30 member with which said catch-means is to be associated, means to connect said rotary-bolt and projectable bolt for simultaneous operation, and means to lock one of said bolts in engaged position.

35 8. In combination, closure locking means comprising a rotary-bolt of the window-fas- tening type and catch-means for engagement thereby, a projectable bolt adapted to be mounted in the closure member upon which 40 said rotary-bolt is to be mounted and to be projectable to a position engaging the closure member with which said catch means is to be associated, means to connect said rotary-bolt and projectable bolt for simultaneous opera- 45 tion, and means to lock said projectable-bolt in engaged position.

9. In combination, closure locking means comprising a rotary-bolt of the window-fas- tening type and catch-means for engagement 50 thereby, a projectable bolt adapted to be mounted in the closure member upon which said rotary-bolt is to be mounted and to be projectable to a position engaging the closure member with which said catch-means is to be 55 associated, means to connect said rotary-bolt and projectable bolt for simultaneous operation, and means to lock said projectable bolt in engaged position more resistant to forcing than the means connecting said bolt for si- 60 multaneous operation to prevent forcing of said projectable bolt by stress applied to said rotary-bolt.

65 10. In combination, closure fastening means comprising a rotary-bolt of the window-fastening type and catch-means for en-

gagement thereby, a tubular body provided with a side-opening and adapted to be mounted in a hole formed in the closure member upon which said rotary-bolt is to be mounted, a projectable bolt-member movably mounted 70 in said tubular body and projectable to engage the closure member with which said catch-means is to be associated and provided with an engageable portion exposed through said side opening, an axial shaft rotatable 75 with said rotary-bolt and extending beyond the attaching face thereof to extend into a hole formed in the closure member upon which said rotary-bolt is to be mounted, and engagement means at the extended end of said shaft to engage the engageable portion of said projectable bolt-member so that rotation of said rotary-bolt into engaging position will simultaneously move said projectable bolt-member into engaging position. 80

11. In combination, closure fastening means comprising a rotary-bolt of the window-fastening type and catch-means for engagement 85 thereby, a tubular body provided with a side-opening and adapted to be mounted in a hole formed in the closure member upon which said rotary-bolt is to be mounted, a projectable bolt-member movably mounted in said tubular body and projectable to engage the closure member with which said catch-means is to be associated and provided with an engageable portion exposed through 90 said side opening, an axial shaft rotatable with said rotary-bolt and extending beyond the attaching face thereof to extend into a hole formed in the closure member upon which said rotary-bolt is to be mounted, a bearing sleeve loosely mounted on said shaft to line the hole into which said shaft extends, and engagement means at the extended end of 95 said shaft to engage the engageable portion of said projectable bolt-member so that rotation of said rotary-bolt into engaging position will simultaneously move said projectable bolt-member into engaging position. 100

12. In combination, closure locking means comprising a rotary-bolt of the window-fas- 105 tening type and catch-means for engagement thereby, a tubular body provided with a side-opening and an internally open detent socket and adapted to be mounted in a hole formed 110 in the closure member upon which said rotary-bolt is to be mounted, a projectable bolt-member movably mounted in said tubular body and projectable to engage the closure member with which said catch-means is to be associated and provided with an engageable portion exposed through said side opening, a 115 spring pressed detent mounted in said bolt-member to engage in said detent socket when said bolt-member is projected, an axial shaft rotatable with said rotary-bolt and extending beyond the attaching face thereof to extend into a hole formed in the closure member upon which said rotary-bolt is to be mounted, 120

125

- engagement means at the extended end of said shaft to engage the engageable portion of said projectable bolt-member so that rotation of said rotary-bolt into engaging position will simultaneously move said projectable bolt-member into engaging position, and means by which said detent may be depressed to enable retraction of said bolt-member.
13. In combination, closure locking means comprising a rotary-bolt of the window-fastening type and catch-means for engagement thereby, a tubular body provided with a side-opening and an internally open detent socket and adapted to be mounted in a hole formed in the closure member upon which said rotary-bolt is to be mounted, a projectable bolt-member movably mounted in said tubular body and projectable to engage the closure member with which said catch-means is to be associated and provided with an engageable portion exposed through said side opening, a spring pressed detent mounted in said bolt-member to engage in said detent socket when said bolt-member is projected, an axial shaft rotatable with said rotary-bolt and extending beyond the attaching face thereof to extend into a hole formed in the closure member upon which said rotary-bolt is to be mounted, engagement means at the extended end of said shaft to engage said engageable portion of said projectable bolt-member so that rotation of said rotary-bolt into engaging position will simultaneously move said projectable bolt-member into engaging position, and means by which said detent may be depressed to enable retraction of said bolt-member, said detent being more resistant to forcing than a part of the structure through which movement of the bolt-member is effected.
14. In combination, closure locking means comprising a rotary cam-bolt of the window-fastening type and catch-means for engagement thereby, a tubular body provided with a side-opening and an internally open detent socket, and adapted to be mounted in a hole formed in the closure member upon which said cam-bolt is to be mounted, a projectable bolt-member movably mounted in said tubular body and projectable to engage the closure member with which said catch-means is to be associated and provided with engagement means exposed through said side opening, a spring pressed detent mounted in said bolt-member to engage in said detent socket when said bolt member is projected, an axial shaft rotatable with said cam-bolt and extending beyond the attaching face thereof to extend into a hole formed in the closure member upon which said cam-bolt is to be mounted, engagement means at the extended end of said shaft to engage the engagement means of said projectable bolt-member so that rotation of said cam-bolt into engaging position will simultaneously move said projectable bolt-member into engaging position, and means by which said detent may be depressed to enable retraction of said bolt-member, said structure embodying a lost-motion connection to enable member drawing movement of the cam-bolt after engagement of said detent in said detent socket.
15. The combination with relatively transversely movable abutting closure members of a surface bolt mounted on one of said members and catch-means for engagement thereby cooperatively mounted on the other of said members, a projectable bolt in the member on which said surface-bolt is mounted and connected to operate simultaneously with said surface bolt, and a recess in the abutting face of the body proper of said other member for engagement by said projectable bolt when the latter is projected so that the closure cannot be opened by "jimmying" or "slicing".
16. The combination with relatively transversely movable abutting closure members of a surface bolt mounted on one of said members and catch-means for engagement thereby cooperatively mounted on the other of said members, a projectable bolt in the member on which said surface-bolt is mounted and connected to operate simultaneously with said surface bolt, a recess in the abutting face of the body proper of said other member for engagement by said projectable bolt when the latter is projected, and means for preventing forcing of said projectable bolt from engaged position by manipulation of said surface-bolt so that the closure cannot be opened by "jimmying", "slicing" or manipulation of said surface bolt.
17. The combination with relatively transversely movable abutting closure members of a surface bolt mounted on one of said members and catch-means for engagement thereby cooperatively mounted on the other of said members, a projectable bolt in the member on which said surface-bolt is mounted, a recess in the abutting face of the body proper of said other member for engagement by said projectable bolt when the latter is projected, means for effecting projection of said projectable bolt upon movement of said surface bolt to engaging position, and means for preventing forcing of said projectable bolt from engaged position by manipulation of said surface-bolt so that the closure cannot be opened by "jimmying", "slicing" or manipulation of said surface bolt.
18. The combination with the meeting rails of a sliding sash, of a projectable bolt mounted within the body proper of the inner of said rails, a recess in the body proper of the outer of said rails to receive the end of said bolt when the latter is projected, and a thimble lining said recess having at least its bottom end hardened to prevent access being ob-

tained to the end of said bolt by drilling from the exterior of said outer rail, said thimble being of greater depth than the extent of projection of said bolt so that said thimble can-
5 not be driven against said bolt member, substantially as and for the purposes described.

19. The combination defined in claim 18, said thimble being provided with flange means at its open end extending beyond the
10 limits of the projectable bolt structure in juxtaposition to the adjacent face of the inner meeting rail, substantially as and for the purposes described.

In testimony whereof, I have signed my
15 name to this specification.

HERMAN H. KISTNER.
